HAROLD F. VIEAU, OF LIVERPOOL, AND EDWARD J. O'NEILL, OF SYRACUSE, NEW YORK,
ASSIGNORS OF ONE-THIRD TO ROY C. HIGBY, OF BIG MOOSE, NEW YORK

RINSING AND DRYING APPARATUS

Application filed June 11, 1927. Serial No. 198,272.

This invention relates to a rinsing and drying apparatus, and more especially to a centrifugal clothes drier provided with means associated with and used in conjunction with the drying apparatus whereby the clothes may be rinsed in the drying receptacle without the necessity of removing the same therefrom.

Therefore the primary object of the invention is to provide, in combination with a centrifugal extractor, means for admitting water to said extractor for the rinsing of clothes therein, after which the rinse water may be removed from the extractor receptacle by centrifugal action applied thereto.

Another object of the invention is to provide in connection with a centrifugal receptacle adapted for use both as a rinsing and a drying chamber, water inlet means constructed in such manner that the water will not at any time come in contact with the machinery for rotating the receptacle, thus overcoming one of the most patent defects heretofore experienced in rinsing devices designed for a similar purpose.

Another object of this invention is to provide a water inlet means as aforesaid which will permit the ingress of water to a combined rinsing and drying receptacle, but at the same time will automatically prevent egress of water from said receptacle, except as the same may be conducted off by centrifugal action of the receptacle.

Another object of the invention is to provide a novel power transmission mechanism and clutch mechanism therefor, which will permit of the installation of the water inlet means aforesaid in connection therewith and in such manner that the proper functioning of each of said elements will not interfere with the functioning of any other of said elements.

A still further object of the invention is the provision of an apparatus of this character, which is comparatively simple in construction, thoroughly reliable and efficient in its purpose, strong, durable, compact, readily assembled and comparatively inexpensive to manufacture and operate.

With the foregoing and other objects in

view, the invention consists in the features of construction, combination and arrangement of parts, as will be hereinafter more specifically described in detail and illustrated in the accompanying drawings, wherein is shown the preferred embodiment of the invention, but it is to be understood that changes, variations and modifications may be made as come properly within the scope of the appended claims without departing from the spirit of the invention or sacrificing any of its advantages.

In the accompanying drawings:

Figure 1 is a side elevation partly in section and broken away of a rinsing and drying apparatus, of the centrifugal type in accordance with this invention.

Figure 2 is a fragmentary view, in vertical section, of the driving and water inlet mechanism of the apparatus.

Figure 3 is a fragmentary view, in section, of the upper portion of the apparatus.

Figure 4 is a top plan view of the apparatus.

A rinsing and drying apparatus, of the centrifugal type, in accordance with this invention, is illustrated by way of example in connection with a washing tank or tub for receiving the overflow from the centrifugal receptacle of the apparatus, but it is to be understood that the overflow can be directed to any other circumferential point desired.

There is illustrated a support, preferably a mobile one, for the elements of the apparatus. The support includes a platform 5, and a carriage 6. Mounted upon the platform and secured thereto is a washing tub or tank 7 which, however, forms no part of this invention. Supported from the platform 5 is an electric motor 8 for furnishing the power to operate all of the mechanism connected with the washing tub or the rinsing and drying apparatus.

A receptacle 9, open at its upper end and preferably of inverted frusto-conical contour is rotatably mounted upon said platform and within said carriage as hereinafter described. Adapted to fit within the receptacle 9 is a foraminous basket 10 corresponding thereto in shape, but of less depth than said recep-

tacle. The receptacle 9 is formed at its top with an outward extension 11, which terminates in a depending flange 12 spaced from the body of the receptacle. The upper face 5 of the extension 9 is transversely corrugated or grooved, as at 13, thus providing exits for the passage of overflow water or the like from the receptacle 9. The rotation of the receptacle 9, causes a centrifugal action which has 10 the effect of extracting from a batch of clothes within the receptacle 9, any water or moisture in the clothes and discharging such water through the exits aforesaid.

The receptacle 9 may be used with or without the basket 10. Said basket 10 is formed 15 with an enlarged reinforced upper rim circular in cross-section, as indicated at 14. This enlarged rim acts to space the basket from the inner wall of the receptacle. Said 20 basket forms no part of the invention claimed herein.

Surrounding and extending above the upper portion of the receptacle 9 is a substantially vertical frame 15 so formed at one portion 25 of the periphery thereof that it may readily be secured to the washing tub 7 or other support. The inner wall of said frame is provided with a groove indicated at 16, while the upper edge of said frame acts as a track 30 for the manually adjustable collecting and directing element.

The manually adjustable overflow collecting and directing element is in the form of a combined trough member and drain board 35 and is generally designated at 17, is mounted above said frame 15, but is formed with an annular flange 18, said flange being adapted to seat snugly within said frame 15, and having in its outer peripheral wall a groove 19 40 adapted, when in position, to register with the groove 16, thus forming a race for the ball bearings 20. This manually adjustable combined trough and drainboard forms no part of the invention herein claimed.

45 The trough member is annular in form, having a bottom 21, an upwardly extending outer wall 22 integral therewith, an inwardly extending flange 23 integral with the top of said outer wall, and an upwardly extending inner wall 24 integral with the bottom 21. Said outer wall 22 is relatively higher with 50 respect to the bottom 21 than is the inner wall 24. The outer wall 22 is cut away for a portion of its circumference as at 25, to provide an outlet for the trough member whereby the discharge from said trough member 55 may be directed by a drain board 26 to any circumferential point desired. The drain board 26 is formed integral with the bottom 21 and outer wall 22, having upstanding side pieces 27 integral with the wall 22 at the ends 60 of the cutout portion 25.

When the receptacle 9 is set up in operative position with respect to the trough member, 65 the depending flange 12 of the receptacle

hooks over the inner wall 24 of the trough member, so that the extension 11 maintains a position in superposed spaced relation to the upper edge of the inner wall 24, while the depending flange 12 extends into the trough 70 member. The trough member is circumferentially adjustable relative to the frame 15, so that the drain board 26 formed integral therewith may be manually adjusted to any selected circumferential point desired. When so 75 adjusted the water or other fluid extracted by the centrifugal action of the receptacle 9 may be directed into the tub 7 or to any other vessel positioned at any point about the apparatus.

80 A cover 28, is adapted to seat upon the receptacle 9, the same being formed with reinforcing webs 29 on its upper face. The marginal portion of the cover member 28 is upset as at 30 to provide what may be termed an annular lip for seating on the top of the extension 11 of the receptacle 9. Said lip is so shaped with respect to the remaining portion of the cover as not to close the exits formed by the corrugations or grooves 13, as clearly 85 illustrated in Figure 3 of the drawings.

90 The cover 28 is provided centrally of its outer face with a socket 31. The inner wall of the socket is formed with an offset or seat portion 32. An annular ring 33 is adapted to be inserted in said socket and rest upon the seat 32 therein. Said ring is formed on its inner wall with a circumferential groove 34. The ring 33 is held within the socket by means of an apertured circular plate 35, preferably in sections, said plate being seated on the upper edge of the wall of the socket 31 and overlying the top edge of the ring 33. Hold-fast elements 36 are then secured 95 through the wall of the socket to the plate 35 to hold the same in fixed position. A lid, hereinafter described in detail, is adapted to cooperate with the cover 28. Said lid is provided with a stub shaft 37 mounted centrally thereof, so positioned that the inner end thereof will register with the socket 31 formed in the cover 28. The inner end of said shaft is reduced and screw threaded. Mounted on the shaft 37 above the inner end thereof is a ring 38 formed with an annular groove 39 in the outer wall thereof. Said ring 38 is held upon said shaft by means of a lock nut 40. When in operative position, the inner wall of the ring 33 is opposed to the outer wall of the ring 38 so that the grooves 34 and 39 will register to form a race for the ball bearings 41. This then permits the cover 28 to rotate freely with respect to the lid 42 upon which it is mounted.

100 The lid 42, previously referred to, is formed laterally thereof with one section of a conventional hinge member, preferably having a pair of angularly disposed lugs 43 extending 105 downwardly to be hingedly secured to the 110

other section 44 of said hinged member, the latter being mounted to the frame 15.

As will be seen, when the lid 42 is closed, it seats upon the top edge of the trough member, 5 thus bringing the cover 28 down upon and into engagement with the top of the receptacle 9, forming a closure for said receptacle. Although the lid 42 is secured in fixed position upon the trough as hereinafter described, yet 10 the cover 28 is at the same time permitted to rotate freely upon the rotation of the receptacle 9.

A conventional latching means is employed for maintaining the lid 42 in closed position 15 and such means may consist of a pair of laterally projecting lugs 45 carried by the lid 42 diametrically opposite the hinge therefor. The lugs 45 are grooved in the tops thereof transversely, to provide seats. Directly below the lugs 45 and secured to the frame 15 is locking member comprising a fixed lug 46 having a cam face on the underside thereof as indicated at 47. Said lug is formed with a vertical opening therethrough adapted to 20 receive a bolt 48 loosely mounted therein, said bolt being formed with a transverse head 49 on the upper end thereof and a nut 50 on the lower end thereof. Said head 49 is provided with a horizontal opening there- 25 through adapted to receive a shackle 51 so that said shackle will be swingingly pivoted to said head. Upon the said bolt 48 and beneath said lug 46 is loosely mounted a latch 52 having a cam face 53 upon the upper side thereof to cooperate with the opposed cam face 47 of the lug 46, said latch being formed with a handle 54.

From the foregoing, it will be seen that when the lid 42 is closed, and the handle of 40 the locking member is thrown to release position, the shackle 51 may be swung up and over and into engagement with the lugs 45, and that thereupon, by swinging the handle of the latch member so as to bring the cam 45 faces into binding engagement, the bolt and shackle secured thereto will be forced downwardly thus causing the lid to be latched or locked into engagement with the trough member.

50 Thus the lid and trough members are locked against rotation when the receptacle is rotated, still the locking is not so tight that the trough member may not be manually adjusted to a certain degree even when the lid is locked.

A clutch mechanism is provided which has a dual function, one of which is to form the connection for rotating the receptacle connected therewith as hereinafter described, and 60 the other is to act as a brake so that stopping the rotation of the receptacle will be gradual and prevent damage thereto.

The aforesaid operating mechanism comprises a stationary collar 55 depending from the platform 5, the lower outer periphery of

said collar being beveled upwardly and outwardly. Secured to the bottom of the receptacle 9 and adapted to pass downwardly through said collar 55 is a rotatable shaft 56. Interposed between the inner wall of the collar 55 and the shaft 56 adjacent the upper end thereof, is mounted a ball bearing member 57 to permit free rotation of the shaft and receptacle secured thereto with relation to said collar and the platform 5. Beneath 70 the collar and keyed to the shaft is a clutch member formed with a central sleeve 58, having at its upper end an outwardly and upwardly extending brake shoe 59 beveled upwardly and outwardly upon the inner periphery thereof and adapted to engage with the outer beveled surface of the collar 55. Said sleeve 58 is also formed at its lower end with an outwardly and downwardly extending clutch shoe 60 beveled downwardly and inwardly on its outer periphery and adapted to coat with a beveled gear 61 loosely mounted upon said shaft 56 for the purpose of driving the latter. The gear 61 is provided with an upwardly extending circumferential flange 62 beveled on its inner periphery upwardly and outwardly for engagement with the outer beveled face of the lower clutch shoe 61 of the sleeve 58. A vertically disposed beveled gear 63 is fixed to a shaft 64 operatively connected with the motor 8 and adapted to mesh with the gear 61. Interposed between the top of the sleeve 58 and the bottom of the ball bearing member 57 is an expansion spring 65 adapted to normally hold the clutch member in engagement with the gear 61. A circumferential flange 66 depends from the platform 5 spaced apart from the collar 55 and to which is secured by suitable means a housing 66 which encloses 100 the aforesaid gearing and clutch member, said housing being adapted to retain oil for the constant lubrication and easy operation of the parts. The shaft 56 is hollow and within said shaft is mounted a water inlet pipe 67 having a beveled valve seat 68 at the upper end thereof adapted to retain a ball valve 69 to prevent the discharge of water from the receptacle through the inlet pipe, but at the same time permitting the inlet of water from the pipe to the receptacle. A water pipe, not shown, is connected at one end to the inlet pipe 67 at 67' and at its other end to a source of water supply. The bottom of the housing 66' is provided with a circumferential opening flanged upwardly at 70 through which opening the inlet pipe 67 passes and into which opening the lower end of the shaft 57 enters. Interposed between the inner wall of the flanged opening 70 and the outer wall of the shaft 57 is a ball bearing member 71 adapted to permit free rotation of said shaft with respect to said flanged opening of the housing 66'. A closure cap member 72 is adapted to be secured around the inlet pipe 130

67 so as to fit snugly within the flanged opening 70 thus providing an oil tight closure for the housing. A convex perforated plate 73 is secured to the bottom of the receptacle 9 5 adapted to limit the upward movement of the ball valve, permit the ingress of water to the receptacle, and prevent the egress of any solid substance that might otherwise clog the valve.

19 The shifting means for the clutching member may be of any conventional type, but I have illustrated and will describe a preferred form of such means and it comprises a rock shaft 74 extending through the housing 66', provided intermediate its ends with a bifurcated crank arm 75 for straddling the sleeve 58 whereby when the shaft 71 is rocked in one direction the crank arm will engage with the underface of the brake shoe 59, 29 thus forcing the clutch member 58 upwardly against the normal expansion of the spring 65, causing the said brake shoe of the clutch member to frictionally engage with the collar 55, producing a braking action to gradually stop the rotation of the receptacle. At the same time the clutch shoe 60 of the sleeve 58 is disengaged from the flange 62 of the gear 61, thus disconnecting the clutch member entirely from the motor. A pull rod 20 76 is secured to a crank 77 carried by one end of the shaft 74 exteriorly of the housing 66'. The rod 76 extends upwardly and is connected to a pivotally supported counterbalanced handle member 78 therefor.

25 When using this apparatus for rinsing purposes the water may be admitted to the centrifugal receptacle either while the same is rotating or while it is stationary. The force of the water upwardly through the 30 perforated plate 73 acts in a manner to agitate the clothes within the receptacle so as to thoroughly rinse them free from any soap, bluing or dirt that may still remain in the clothes. It should also be understood 45 that whether the receptacle is being rotated or is stationary, any overflow therefrom will be carried to any selected circumferential point by means of the manually adjustable combined trough and drainboard positioned 50 at the top of the receptacle. When rotated, this overflow is caused by the centrifugal action of the receptacle.

What we claim is:

55 1. In an apparatus for the purpose set forth, a vertically disposed rotatable receptacle forming a combined rinsing and drying chamber, an adjustable drain board, means carried at the top of the receptacle to 60 permit of adjustably positioning said board circumferentially with respect to the receptacle for directing the overflow from said chamber to the point desired, and a rotatable vertically disposed hollow shaft connected 65 with and opening into the bottom of said

receptacle for operating the latter and supplying water to the chamber.

2. In an apparatus for the purpose set forth, a vertically disposed rotatable receptacle forming a combined rinsing and drying chamber, an adjustable drain board carried at the top of the receptacle for directing the overflow from said chamber, a rotatable vertically disposed hollow shaft connected with 70 and opening into the bottom of said receptacle for operating the latter and supplying water to the chamber, and a guard secured to the upper face of the bottom of said receptacle and spaced from the upper end of said shaft.

75 3. In an apparatus for the purpose set forth, a vertically disposed rotatable receptacle forming a combined rinsing and drying chamber, a vertically disposed rotatable hollow shaft connected with the bottom of and opening into said receptacle for operating and supplying water to the latter, a perforated guard secured to the upper face of the bottom of said receptacle and spaced from the upper end of said shaft, and means for 80 operating said shaft.

85 4. In an apparatus for the purpose set forth, a vertically disposed rotatable receptacle forming a combined rinsing and drying chamber, a vertically disposed rotatable hollow shaft connected with the bottom of and opening into said receptacle for operating and supplying water to the latter, a perforated guard secured to the upper face of the bottom of said receptacle and spaced from the upper end of said shaft, means for 90 operating said shaft, a water conducting pipe extending into said shaft, said pipe having the upper portion of its inner face bevelled to provide a valve seat, and a check valve associated with said seat.

105 5. In an apparatus for the purpose set forth, a rotatable receptacle forming a combined rinsing and drying chamber, a rotatable vertically disposed hollow shaft connected to and opening into the bottom of said receptacle for operating the latter, operating means for said shaft, braking means for said shaft, and a valve controlled water conducting pipe opening into said shaft, the valve of said pipe being positioned at that end thereof arranged in said shaft.

110 6. In an apparatus for the purpose set forth, an open top centrifugal receptacle, a closure for said top, a rotatable, driven shaft fixed thereto for revolving it, driving means for said shaft, means surrounding the shaft and including a spring controlled shiftable part and a stationary part, the former normally engaging said driving means for coupling the latter to the shaft, and means for 115 shifting said spring controlled part against the action of its controlling spring to engage said stationary part to provide a brak- 120

- ing action for the receptacle and to unclutch said driving means for the shaft.
7. In an apparatus for the purpose set forth, a centrifugal open top receptacle, a closure for said top, means connected to the bottom of the receptacle for revolving the latter, means including a shiftable combined clutching and braking element for discontinuing the operation of said revolving means for the receptacle and for applying braking action thereto, said means for revolving the receptacle including a hollow rotatable shaft, and a stationary, valve controlled water supply pipe extending through said shaft for communication with the receptacle, the said means including the clutching and braking element further including a stationary part coacting with the latter to provide for the braking action.
- 10 8. In an apparatus for the purpose set forth, an open top centrifugal receptacle, a closure for said open top, operating means for the receptacle, means including a stationary part and a spring controlled bodily shiftable combined clutching and braking element for discontinuing the operation of said operating means and to provide a braking action for said operating means, and a stationary, valve controlled water supply pipe for communication with the receptacle and extending through said operating means.
- 15 9. In an apparatus for the purpose set forth, a closable centrifugal receptacle having overflow exits at its top, an adjustable, combined overflow collecting and directing element mounted over and carrying a closure for said receptacle, operating means for the receptacle, and water supply means opening into the receptacle.
- 20 10. In an apparatus for the purpose set forth, a closable centrifugal receptacle having overflow exits at its top, an adjustable, combined overflow collecting and directing element mounted over and carrying a closure for said receptacle, operating means for the receptacle, and water supply means opening into the receptacle, said water supply means being valved controlled and extending through said operating means.
- 25 11. In an apparatus for the purpose set forth, a closable centrifugal receptacle having overflow exists at its top, a support for the receptacle, said support including a depending collar operating means for the receptacle, and means for discontinuing the operation of the operating means and coacting with said collar to provide a braking action for the receptacle on the stoppage of said operating means.
- 30 12. In an apparatus for the purpose set forth a closable centrifugal receptacle having overflow means at its top, a closure for the receptacle, a vertical shaft connected to and operating the receptacle, means sur-
- rounding the lower portion of the shaft for driving it, a stationary collar surrounding and spaced from the upper portion of said shaft, and a shiftable, spring controlled combined clutching and braking element slidably mounted on and connected to said shaft between said collar and operating means and providing for normally clutching the latter to the shaft and further providing when shifted from normal the unclutching of said operating means and to coact with said collar to provide a braking action for the receptacle.
- 35 13. In an apparatus for the purpose set forth a closable centrifugal receptacle having overflow means at its top, a closure for the receptacle, a vertical shaft connected to and operating the receptacle, means surrounding the lower portion of the shaft for driving it, a stationary collar surrounding and spaced from the upper portion of said shaft, a shiftable, spring controlled combined clutching and braking element slidably mounted on and connected to said shaft between said collar and operating means and providing for normally clutching the latter to the shaft and further providing when shifted from normal the unclutching of said operating means and to coact with said collar to provide a braking action for the receptacle, said shaft being hollow, and a water supply means for the receptacle extending through the shaft and having a check valve at its inner end.
- 40 14. In an apparatus for the purpose set forth a centrifugal receptacle, a shaft connected thereto for operating it, operating means for the shaft surrounding one end thereof, a stationary collar surrounding and spaced from the shaft and further spaced from said operating means, and a shiftable spring controlled combined clutching and braking element slidably mounted on and connected to said shaft between the collar and operating means and providing for normally clutching the latter to the shaft and further providing when shifted from normal position the unclutching of said operating means and to coact with said collar to provide a braking action for the receptacle.
- 45 15. In an apparatus for the purpose set forth a centrifugal receptacle, a shaft flanged at one end, means for securing the flange of the shaft to the receptacle, operating means for the shaft surrounding the other end thereof and provided with a beveled flange, a stationary collar surrounding and spaced from the shaft and further spaced from said operating means and having a beveled periphery, and a shiftable, spring controlled combined clutching and braking element slidably mounted on and connected to said shaft between the collar and said operating means and normally engaging with said beveled flange for clutching the operating means to the shaft and further providing when

shifted from normal position the unclutching of said operating means and to coat with said beveled periphery to provide a braking action for the receptacle.

5 16. In an apparatus for the purpose set forth a centrifugal receptacle, a shaft connected thereto for operating it, operating means for the shaft surrounding one end thereof, a stationary collar surrounding and spaced from the shaft and further spaced from said operating means, a shiftable spring controlled combined clutching and braking element slidably mounted on and connected to said shaft between the collar and operating means and providing for normally clutching the latter to the shaft and further providing when shifted from normal position the unclutching of said operating means and to coat with said collar to provide a braking action for the receptacle, said shaft being hollow, and a water supply means for the receptacle extending through the shaft and having a check valve at its inner end.

25 17. In an apparatus for the purpose set forth a centrifugal receptacle, a shaft flanged at one end, means for securing the flange of the shaft to the receptacle, operating means for the shaft surrounding the other end thereof and provided with a beveled flange, a stationary collar surrounding and spaced from the shaft and further spaced from said operating means and having a beveled periphery, a shiftable, spring controlled combined clutching and braking element slidably mounted on and connected to said shaft between the collar and said operating means and normally engaging with said beveled flange for clutching the operating means to the shaft and further providing when shifted from normal position the unclutching of said operating means and to coat with said beveled periphery to provide a braking action for the receptacle, said shaft being hollow, and a water supply means for the receptacle extending through the shaft and having a check valve at its inner end.

35 18. In an apparatus for the purpose set forth a centrifugal receptacle, a shaft connected thereto for operating it, operating means for the shaft surrounding one end thereof, a stationary collar surrounding and spaced from the shaft and further spaced from said operating means, a shiftable spring controlled combined clutching and braking element slidably mounted on and connected to said shaft between the collar and operating means and providing for normally clutching the latter to the shaft and further providing when shifted from normal position the unclutching of said operating means and to coat with said collar to provide a braking action for the receptacle, said shaft being hollow, a water supply means for the receptacle extending through the shaft and having a check valve at its inner end, and a

strainer fixed to the receptacle and extending across the inner end of said water supply means.

19. In an apparatus for the purpose set forth a centrifugal receptacle, a shaft flanged at one end, means for securing the flange of the shaft to the receptacle, operating means for the shaft surrounding the other end thereof and provided with a beveled flange, a stationary collar surrounding and spaced from the shaft and further spaced from said operating means and having a beveled periphery, a shiftable, spring controlled combined clutching and braking element slidably mounted on and connected to said shaft between the collar and said operating means and normally engaging with said beveled flange for clutching the operating means to the shaft and further providing when shifted from normal position the unclutching of said operating means and to coat with said beveled periphery to provide a braking action for the receptacle, said shaft being hollow, a water supply means for the receptacle extending through the shaft and having a check valve at its inner end, and a strainer fixed to the receptacle and extending across the inner end of said water supply means.

20. In an apparatus for the purpose set forth a support, an open top centrifugal receptacle arranged thereover and having a water intake, a closure for said open top, said support having a stationary part depending therefrom, a rotatable shaft for and connected to said receptacle, driving means for the shaft, and a spring controlled, bodily shiftable element slidably keyed to the shaft and including a clutching shoe engageable with said driving means for coupling it to the shaft when the bodily shiftable element is in one position and further including a brake shoe coating with said stationary part when the bodily shiftable element is in another position to apply a braking action to the shaft, and a valve controlled water supply pipe extending through said shaft to said intake.

21. In an apparatus for the purpose set forth a support, an open top receptacle arranged thereover, a closure for said open top, said support having a stationary part depending therefrom, a rotatable shaft for and connected to said receptacle, driving means for the shaft loosely mounted thereon, and a spring controlled, bodily shiftable element slidably keyed to the shaft and including a clutching shoe engageable with said driving means for clutching it to the shaft to provide for the operation of the latter when the bodily shiftable element is in one position and said bodily shiftable element further including a brake shoe coating with said stationary part when the bodily shiftable element is in another position to apply a braking action to the shaft.

22. In an apparatus for the purpose set

forth a support, an open top centrifugal receptacle arranged thereover, a closure for said open top, a rotatable shaft provided with a flange fixedly secured to said receptacle whereby the latter will bodily move with the shaft, bearing means carried by said support for said flange, driving means for the shaft loosely mounted thereon, and a spring controlled, bodily shiftable element slidably keyed to the shaft and including a clutching shoe engageable with said driving means for coupling it to the shaft for operating the latter when the bodily shiftable element is in one position, said support having a depending, annular, beveled stationary part, said bodily shiftable element further including a brake shoe coacting with said stationary part when the bodily shiftable element is in another position to apply a braking action to the shaft on the clutching of the driving means on the latter.

23. In an apparatus for the purpose set forth a support having a depending stationary part, an open top centrifugal receptacle arranged over the support, a rotatable shaft provided at one end with a flange fixedly secured to the receptacle whereby the latter will be carried with the shaft, bearing means carried by said support for said flange, a gear loosely mounted on said shaft for operating it, a bearing means for the other end of the shaft and providing a stop for limiting the shift of said gear in one direction, and a bodily shiftable element slidably keyed to the shaft and including a clutching shoe coacting with said gear for clutching it to the shaft to provide for the operation thereof and further including a braking shoe coacting with said stationary part to apply a braking action to the shaft when the latter is unclutched from said gear.

In testimony whereof, we affix our signatures hereto.

45 HAROLD F. VIEAU.
EDWARD J. O'NEILL.
